APPARATUS FOR CLEANING CASTINGS

Towner K. Webster, Jr., Winnetka, Ill., assignor to The Hydro-Blast Corporation, Chicago, Ill., a corporation of Illinois

Application July 22, 1937, Serial No. 154,988

1 Claim. (Cl. 51—13)

This invention relates to apparatus for cleaning castings, and more particularly to a structure utilizing a sand blast device for automatically cleaning castings.

5 Usually when small castings are removed from the sand molds, they are placed in a tumbling barrel with a charge of small pieces of irregularly shaped metal known as tumbling stars, and the whole tumbled until the surfaces of the castings are cleaned of adhering sand and scale by the abrading action developed. When sufficiently cleaned, the tumbling barrel is opened, the load discharged and the castings removed from the dirt and tumbling stars.

10 15 During the above operation much metallic and silica dust is produced, which necessitates the use of suction ventilation to guard the operators against silicosis.

In the present invention it is proposed to clean 20 small castings continuously without stopping the machine, or in batches, and to accomplish this cleaning operation much more rapidly and without the production of the usual dangerous dust.

It is an object of my invention to provide means 25 for cleaning castings in a continuous operation, or in batches as desired.

A further object is to eliminate the formation of dust from a casting cleaning operation.

Another object is to provide an automatic casting 30 cleaning machine that uses high pressure liquid jets containing entrained abrasive particles to abrade the surfaces of the castings as they pass therethrough.

A further object is to use the abrading stream 35 both for cleaning the castings and for propelling them through the machine.

A further object is to provide means for regulating the speed of travel of the castings through the machine.

40 A further object is to provide a machine for cleaning castings in which the castings are both cleaned and moved through a machine by a hydraulic abrading stream.

A further object is to provide means for cleaning 45 castings in batches in a substantially closed machine by means of abrasive carrying liquid jets.

These and other objects will become apparent from the following description, reference being had to the accompanying drawings in which:

50 55 Fig. 1 is a side elevation partly in section of a machine according to this invention;

Fig. 2 is an elevation of the discharge end of the machine while Fig. 3 is an elevation of the inlet or charging end of the machine;

Fig. 4 is a sectional view taken in the direction

of the arrows along the line 4—4 of Fig. 1, showing a rotatable drum with a blasting gun mounted therein;

Fig. 5 is a sectional detail view of the cylinder tilting mechanism;

Fig. 6 is a sectional view of the drive mechanism taken in the direction of the arrows along the line 6—6 of Fig. 1;

Fig. 7 is a view in elevation of one of the blasting guns with the cap of the ball and socket 10 clamping bracket removed;

Fig. 8 is a sectional view partly in elevation of the gun clamping means taken in the direction of the arrows along the line 8—8 of Fig. 7.

In the drawings in which like numerals designate like parts throughout the same, the machine in general consists of a rotating cylinder into which are projected several abrasive carrying high pressure liquid streams. The word cylinder is above and hereafter used, refers to a rotating tumbler which may be round, square, triangular, or of any other shape or cross section, and thus the word cylinder in the claims is intended to cover any such structure. The castings are fed into one end of the cylinder and tumbled by its rotation, while the abrading streams play upon and clean the surface of dirt and scale. The impact of these abrading streams also moves the castings forward and out of the opposite end of the cylinder. To regulate the speed of travel of the castings through the machine the cylinder is tiltable on a horizontal transverse axis, so that when the charging end is tilted downwardly the rate of travel of the castings will become slower, while if tilted in the opposite direction, the castings will move more rapidly toward the discharge end.

The casting cleaning machine 10 is installed over a shallow rectangular concrete pit 12 which serves to catch the water, sand and mud flowing therefrom. The pit 12 slopes in all directions toward the center where it opens at 14 into a sand classifier 16 and storage tank 18 below.

Near the center of the side edges of the pit 12 are secured bearing blocks 20 and 22, each of which has a cylindrical upper bearing surface 24 and 26, with these surfaces 24 and 26 in axial alignment.

The machine 10, which rests upon the blocks 20 and 22, consists of a horizontal rectangular frame 50 55 28 built up of four channel iron sections suitably secured together at their ends by welding or riveting. Brackets 30 and 32 are secured to the outside faces of each of the side members of the frame 28 near their centers and have hemicylin- 55

drical grooves 34 fitted to the cylindrical surfaces 24 and 26. Thus when the frame 28 is placed above the pit 12 with the grooves 34 fitted to the surfaces 24 and 26 of the bearing blocks 20 and 5 22, it will be seen that the frame 28 is free to rock about a transverse axis through the center of the hemicylindrical grooves 34.

The left hand side member of the frame 28, looking at the machine from the end shown in 10 Fig. 3, carries near its center a horizontal platform 36 positioned above the bearing block 30. Secured to this platform 36 is an electric motor 38 geared through any suitable speed reduction means 40 to a horizontal shaft 42. The shaft 42 15 extends parallel to the side member of the frame 28 and is journaled in a plurality of aligned bearing boxes, in this instance six, four of which 44, 46, 48 and 50, are in view, the other two being hidden by the motor 38.

20 Near one end of the frame 28 between the bearing boxes 44 and 46, a gear 52 is keyed or otherwise rigidly secured to the shaft 42. This gear 52 is flanked on its sides by rollers 54 and 56 which are secured to the shaft 42 and have a diameter equal to the pitch diameter of the gear 52. The other end of the shaft 42 is similarly provided with a gear 62, and rollers 64 and 66, while the center carries one wide roller (not shown).

30 The other side member of the frame 28 also carries a shaft provided with rollers similar to the one above described, excepting that it carries no gears and idles instead of being driven by the motor 38.

35 The above described rollers serve as the support for a rotatable drum 68, which is provided with circumferential tracks 70, 72 and 74, to register with the three sets of rollers. The two end tracks 70 and 74 are provided centrally with ring gears 40 76 and 78 having a pitch diameter equal to the diameter of the tracks 70 and 74, which mesh with the gears 52 and 62 respectively. Therefore, when the motor 38 revolves the shaft 42, the gears 52 and 62 will drive the cylinder 68 through 45 ring gears 76 and 78, while the weight of the cylinder 68 will be carried on the above described rollers.

The drum 68 is made of boiler plate or other suitable material and may be lined with rubber or 50 fabric belting 80, since these materials resist abrasion much better than do metals.

The ends of the frame 28 have secured thereto upright rails 82 and 84 at one end and 86 and 88 at the other, which carry disc-shaped closures 90 55 and 92 for the ends of the cylinder 68. A U-shaped annular ring 94 and 96 is secured to the inner periphery of the discs 90 and 92, respectively, and forms a labyrinth with flanges 98 and 100 secured to the ends of the cylinder 68, thereby 60 preventing the blasting guns from splashing sand and water from around the periphery of the cylinder ends, while permitting the cylinder 68 to revolve relative to the end closures 90 and 92.

The lower surface of the annular U-shaped 65 members 94 and 96 is somewhat flattened at 102 and bolted or otherwise suitably secured to the top flanges of the end cross members of the frame 28, thereby providing additional support for the cylinder and closures. The inside flanges 70 of the U-shaped annular rings 94 and 96 are cut away at the bottom where the rings rest upon the frame 28 to provide an opening 104 for the flow of water, sand, and mud from the ends of the cylinder 68 through into the pit 12.

75 The means for adjusting the degree of tilt of

the cylinder consists of a screw shaft 106 swivelably anchored to the bottom of the pit 12 by the bracket 108. The upward end of the screw 106 extends through a round nut 110 rotatably held between two arms of a yoke 112 that is secured to the upright frame rail 82. The round nut 110 is provided with a plurality of radially spaced vertical slots 114 that may be engaged by a pawl 116 slidably secured at 117 to a horizontally swingable lever 118. The lever 118 is provided near its free end with a handle 120 and grip 122 to be grasped in one of the operator's hands. The grip 122 is pivotally mounted on the lever 118 at 124 and urged outwardly by a spring 126. This grip 122 is connected through suitable bell crank mechanism 15 to the pawl 116, so that when the grip 122 is squeezed against the handle 120, the pawl will be retracted from the nut 110, and when the grip 122 is released the spring 126 will urge the pawl 116 into one of the slots 114 of the nut 110. It will 20 thus be seen that when the lever 118 is oscillated backward and forward with the grip 122 released at the end of the forward stroke and compressed at the end of the backward stroke, the nut 110 will be revolved from left to right, thereby raising 25 the cylinder 68. Likewise, if the same oscillations are carried out, but the grip released at the end of the backward stroke and compressed at the end of the forward stroke, the attached end of the cylinder 30 68 will be lowered.

In order to produce a better spreading of the castings being tumbled in the lower portion of the cylinder 68, a plurality of spaced cleats 128 are secured to the inner surface and extend substantially the length of the cylinder.

35 The cylinder end closure shown in Figs. 1 and 3 is provided near its top with a hopper 130 and opening 132 through which the castings to be cleaned may be placed into the cylinder 68. Below the hopper 130 another opening 134 is provided through which high pressure abrasive carrying liquid streams may be projected against the castings within the cylinder from guns 136 and 40 138 which are mounted on the lower surface of the hopper 130 as shown in Figs. 1 and 3.

45 Inside the cylinder 68 two more guns 140 and 142 are mounted on a beam 144 that extends longitudinally of the cylinder and is secured at its 50 ends to the end walls 90 and 92.

55 All four of these guns 136, 138, 140, and 142 are preferably interchangeable and similar. Substantially all of the operating features of a hand held gun have been retained, including an adjusting screw 145 for varying the character of the discharged stream, but the housing projecting from the rear of the gun ends in a ball 146 through which projects a stem 148 of a water inlet valve within the gun housing. A knob 150 secured to the end of the stem 148 serves as a means to revolve the stem 148 and adjust the water valve.

60 The ball 146 is held in a socket joint 152, best shown in Figs. 7 and 8, which consists of a base portion 154 secured to either the hopper 130 or beam 144, as the case may be. The top surface of this base portion 154 has a spherical depression to take the ball 146 and a transverse cylindrical depression crossing the spherical depression to allow passage of the shank of the gun body and the stem 148.

65 The cap 156 of the socket joint 152 has an interior or lower surface similar to the upper surface of the base 154 and is secured to the base 70 75

154 by two bolts 158 and nuts 160. The cap 156 and base 154 are so proportioned that when the nuts 160 are drawn up tightly, the ball 146 will be held rigidly within the interior surface of the socket 152, but when the nuts 160 are loosened, the ball 146 and attached gun may be freely swiveled within certain limits to adjust the angularity of the gun and projected stream. By this means, the streams projected from the four guns may be 10 adjusted to play upon the castings within the cylinder 68 in the most efficient manner.

The discharge end of the cylinder 68 shown in Figs. 1 and 2 has its closure provided with an opening 162 through which the cleaned castings may be discharged from the machine. Slanting from the lower surface of the opening 162 toward a conveyor belt, or what ever means is used to collect the cleaned castings, is a chute 164 which is built up of ribs 166 over which the castings slide or roll, while the spaces between the ribs allow the water to run through into the pit 12. Each side of this chute 164 is provided with upstanding panels 166 which prevent the castings from falling from the sides of the chute. 25 A sliding door 168, shown in its raised position in Fig. 2, may be lowered to cover the opening 162 when it is desired to confine the castings within the cylinder for an extended period rather than having them move through the cylinder 30 continuously.

Each of the guns 136, 138, 140 and 142 is connected by a hose length 170 to a manifold 172 supplied with water under approximately 700 pounds to the square inch pressure from a motor 35 driven compressor, not shown, through the pipe 174. Each gun is also connected to a hose length 176 which leads to separate sand feeders 178 which have their inlets 180 submerged in the sand contained in the tank 18.

40 These sand feeders 178 as well as the guns and sand classifier 16 are all fully described in application Serial No. 127,620, now Patent No. 2,200,587, dated May 18, 1940, and reference is made to that patent for a fuller explanation of 45 the constructional features of these units. It should be noted in this connection, however, that I prefer to use a separate sand feeder 178 for each gun, since the characteristics of these feeders vary greatly depending on the amount of sand flowing through them, and although one feeder could be built to supply all four guns, it would not operate efficiently if one or more of the guns were shut off. Consequently it increases the flexibility of the machine to meet varying circumstances to provide it with guns, any one of which may be turned off at will without disturbing the operation of the others.

In operation, the machine is installed and connected as above described. With the motor 38 energized through a proper electric circuit, the cylinder 68 is revolved through the drive shaft 42 and gears 52, 62 and 76, 78, the gun valves 150 are turned on and the character of the discharged stream regulated by the adjusting screw 145.

The castings to be cleaned are placed in the cylinder 68 through the opening 132 and the streams from the four guns are directed to obtain the most efficient cleaning action and to urge the castings toward the discharge opening 162. If it is seen that the castings move too rapidly through the machine, the nut 110 is revolved by the handle 120 to lower the rear end of the cylinder 68, while if the castings stay in the cylinder longer than necessary, the rear end 10 of the cylinder is raised.

It will be seen that by the tilting of the cylinder and the adjustability of the guns, great flexibility of operation is possible, thereby allowing castings of varying character to be cleaned in 15 this machine. After the machine is adjusted as above described, castings may be continuously fed into the hopper 130 and they will be cleaned and discharged from the opening 162 automatically.

The discharged water and sand, plus the dirt 20 abraded from the surface of the castings runs into the pit 12 and through the openings 14 into the sand classifier 16. This classifier, as described in application Serial No. 127,620, now Patent No. 2,200,587, dated May 14, 1940, allows the proper 25 grade of sand to fall through into the tank 18 while rejecting the large particles and sludge. The sand in the tank 18 is then drawn into the feeders 178 through the holes 180 and recirculated to the guns.

While I have described and illustrated a preferred embodiment of my device, it is to be understood that variations may be made therefrom without departing from the scope of this invention 35 and that the limitations on this invention are to be found in the appended claim.

I claim:

In casting cleaning apparatus, the combination comprising a rotatably mounted cylinder in which castings are cleaned, means for rotating 40 the cylinder, end covers for the cylinder, one of which has a discharging opening therein and the other of which has a charging opening and a second opening therein, support means for the cylinder including a fulcrum and cooperating 45 adjustable means for controlling the axial slope of the cylinder, a pair of guns, means providing a supply of fluid under pressure and abrasive material to the guns to be discharged thereby as jets, one of the guns being outside of the cylinder adjacent the charging opening and extending toward the said second opening, the other of the guns being within the cylinder, and means for supporting the guns including adjustable ball and socket joints for determining the angular 50 positions of the guns, the angular positions of the guns being such that the jets urge the castings from the charging opening and to the discharging opening, and the angular position of the guns and axial slope of the cylinder being 55 so adjusted and related that the castings are cleaned by the jets in moving from the charging opening to the discharging opening.

TOWNER K. WEBSTER, JR.
